INVENTOR

James A. Smith,
by his attorney,
J. Edward Sheband.

UNITED STATES PATENT OFFICE.

JAMES A. SMITH, OF BUFFALO, NEW YORK.

FLEXIBLE-SHEET FORM FOR SOFT CUFFS.

1,342,032.

Specification of Letters Patent. Patented June 1, 1920.

Application filed July 31, 1918. Serial No. 247,624.

To all whom it may concern:

Be it known that I, JAMES A. SMITH, a citizen of the United States, residing at Buffalo, in the county of Erie and State of New York, have invented certain new and useful Improvements in Flexible-Sheet Forms for Soft Cuffs, of which the following is a specification, reference being had to the accompanying drawings and to figures of reference marked thereon.

Like figures of reference refer to like parts.

This invention relates to flexible sheet forms for use in maintaining an unwrinkled appearance in soft French cuffs when worn.

One of the objects of my invention is to provide a sheet form to be placed within the fold of a French soft cuff to give an even edge to the same and keep the said cuff smooth as originally laundered.

Another object is to provide a readily detachable sheet form for the soft cuff, which will be kept mainly in place by engaging the cuff-link.

With these and other objects my invention resides in certain constructions, one embodiment of which is illustrated in the drawings, its application is explained and what I claim is set forth.

30 In the drawings,

Figure 1 is an elevation of a flexible sheet form for soft cuffs, which embodies my invention.

Fig. 2 is a side elevation of a sleeve end showing the form illustrated in Fig. 1 embodied therewith.

Fig. 3 is an end elevation of the sleeve end and form shown in Fig. 2.

Fig. 4 is a top plan of the sleeve end shown 40 in Figs. 2 and 3.

In the figures, to the fragment 1 of a sleeve end is shown attached the ordinary soft French cuff 2, having an outer flap 3, in which are the link-button holes 9^a, 9^a.

45 Beneath the flap 3 is shown the flexible sheet form 5, having a straight upper edge 6 ending in square corners 7, 7, which when in place beneath the flap 3, reach within a very short distance of the edge 8 of the cuff 2, the corners 7, 7 being only sufficiently back from the edges 8, 8 to be visibly covered, it being my intention to have the corners 7, 7 of the form 5, give firmness to the corners 9, 9 of the cuff 2.

55 The link-button 10 is shown positioned at the outer corner of the hole 9^a, it being

forced into this position by engagement with the notch 11 of the form 5, which engages the link 12 of the link-button 10. I preferably use stiff link-buttons on account 60 of their firmness in holding the parts in place. The lower edges 13, 13 of the form 5 are cut back from the corner 14 of the cuff 2, so that when the corner 14 moves partially out of place, the form 5 will not be ex- 65 posed.

As an additional precaution to retain the form 5 in its proper place, I provide a slot 15 in the form 5 at its center near its lower edge, and have a similarly placed button 70 hole in cuff 2, near the sleeve 1, having the slot 15 and the last named button hole engaged by a small flat-ended stud 16. I find that, ordinarily, no additional fastening, such as the button or stud 16 is necessary, as 75 the form 5 usually stays up in place at its central portion. The stud 16 is also adapted to retain the form in the cuff when the latter is unbuttoned so that the cuff may be unbuttoned freely without displacing the form. 80

Referring particularly to the shape of the form 5, as illustrated in Fig. 1, attention is called to the shape of the notches 11, 11, the inner parts thereof being made V-shaped so as to facilitate the gravitating of the link 85 12 of the link-button 10, into the corners 11^a, 11^a, while the outer corners 11^b, 11^b are squared toward each other to reduce the opening 11^c to what it otherwise would have been, had the inclined edges, starting at the 90 corner 11^a, been extended straight to intersect the edge 7^a at an obtuse angle. The reduction of the opening 11^c gives more body in the form 5 in supporting the flap 3 at the hole 9^a. The broken line surrounding the 95 form 5 of this figure illustrates the outline of the spread out flap 3 to show the relative position of the form 5 thereto.

As changes in the details of the form 5 may be made in the same without departing 100 from the invention embodied therein, I do not wish to be confined to the one form herein shown. The same features of this invention may be used in a form adapted for use with soft collars. So, this invention may be said to apply to both cuff and collar shirt bands. I do not wish to be confined to the use of the button or stud 16, as any other suitable means of attachment may be substituted therefor.

110 Having described my invention, I claim,
1. A form for giving a neat shape to an

ordinary French cuff, said form comprising a flat flexible sheet having an angular notch in each of its transverse edges, the apexes of said notches being spaced a distance equal to the distance between the outer corner of the band link holes so that a link directly engaging said notches and in contact with said form and passing through said holes is positioned by said form in the outer extremity of the said holes, whereby the band is held longitudinally extended and flat in appearance and the form retained in place against longitudinal and transverse movement without necessitating any alteration in the construction of the said ordinary French cuff, said form affording a continuous surface support of substantially uniform width between the parallel edges of the cuff and being of a width to maintain the entire cuff in a smooth and stiffened condition.

2. A form for giving a neat shape to an ordinary French cuff, said form comprising a flat flexible sheet having an angular notch in each of its transverse edges, the apexes of said notches being spaced a distance equal to the distance between the outer corners of the cuff link holes, so that a link directly engaging said notches and in contact with said form and passed through said holes is positioned by said form in the outer extremity of said holes, whereby the band is held longitudinally extended and flat in appearance and the form retained in place against longitudinal and transverse movement with-

out necessitating any alteration in the construction of the said ordinary French cuff, said form affording a continuous surface support substantially of uniform width between the parallel edges of the cuff and being of a width to maintain substantially the entire cuff in a smooth and stiffened condition, and means midway of the transverse edges of the form for detachably securing the form within the cuff and adapted to retain the form in the cuff when the same is unbuttoned.

3. A form for giving a neat shape to an ordinary French cuff having the usual link button holes and fastening link, said form having a straight outer edge to fit against the inner edge of the longitudinal front of said cuff and the inner corners of the form being cut away and each end of the form being provided with an angular notch in its transverse edge, the apexes of the notches being spaced a distance equal to the distance between the outer corners of the link button holes so that the link directly engaging said notches and in contact with said form and passing through said holes is positioned by said form in the outer extremity of said holes, said form affording a continuous surface support of substantially uniform width between the parallel edges of the cuff and being of a width to maintain substantially the entire cuff in a smooth and stiffened condition.

Buffalo, N. Y., July 30, 1918.
JAMES A. SMITH.
